UNITED STATES PATENT OFFICE.

JAY S. CORBIN, OF GOUVERNEUR, NEW YORK.

DISK-HARROW.

SPECIFICATION forming part of Letters Patent No. 325,224, dated August 25, 1885.

Application filed July 24, 1884. (No model.

To all whom it may concern:

Be it known that I, JAY S. CORBIN, a citizen of the United States, residing at Gouverneur, in the county of St. Lawrence and State of New York, have invented certain new and useful Improvements in Disk-Harrows, of which the following is a specification, reference being had therein to the accompanying drawings.

10 The object of one part of this invention is to provide for the adjustment of the disk-gangs relative to each other and upon a line transverse to the line of draft in that class of harrows in which the disk-gangs are mounted in the lower ends of pendent hangers in such manner that the gangs can vibrate in both horizontal and vertical planes, the gangs in this class of harrow being connected with the lower ends of the hangers by means of universal joints, or equivalents therefor, the hangers being non-rotating and bolted rigidly to the frame.

15 Other parts of the invention relate to details of construction, which will be hereinafter fully explained.

20 Figure 1 is a rear elevation of my improved harrow. Fig. 2 is a top or plan view. Fig. 3 is an end elevation, two disks and a gang-axle having been broken away on the line $z z$, Fig. 1. Fig. 4 is a vertical section, enlarged, 25 of part of the harrow, taken on line $z z$, Fig. 1. Fig. 5 is a rear elevation of Fig. 4. Fig. 6 is a vertical section on the line $y y$, Fig. 4, looking in the direction of the arrow 1, Fig. 4. Fig. 7 is a top or plan view of the hanger and 30 one of the shaft-bearings. Fig. 8 is a bottom view of one of the shaft-bearings, enlarged, with its supporting-bolt indicated in dotted lines. Fig. 9 is a horizontal section of the same bearing, enlarged, taken on line $x x$, Fig. 40 5. Fig. 10 is a central vertical section, reduced in size, of a gang-axle and part of one of the hangers.

35 In the drawings, A is the tongue, and A' the seat.

40 B is a cross-bar or transverse bar bolted firmly to the rear end of the tongue and transverse thereto.

45 C C' C² C³ constitute a non-rotating pendent hanger, and as the devices at each end of the 50 transverse bar B are substantially alike, I will confine my description to those at the right-hand end of the said bar.

Referring particularly to Figs. 3, 4, 5, 6, and 7, C is the vertical part of the non-rotating hanger expanded at its upper end into a horizontal arm or plate, C', which is slotted lengthwise, as indicated in Fig. 7, and is secured firmly and adjustably to the under side of transverse bar B by means of a bolt, b', which passes through the slot, through a hole in the transverse bar, and preferably through a saddle, b, placed on top of the bar, the outer ends of this saddle turning downwardly over the edges of the bar, and thereby strengthening it against being split by the bolt b. The 55 lower end of the hanger is forked, one leg, C², of this fork projecting forward on a substantially horizontal line, and then downward on a substantially vertical line, its lower end having a hole to receive a bolt, to be hereinafter referred to. The rear leg, C³, extends in a substantially vertical line to about the same distance below the transverse bar as does the leg C², and is also provided with a hole to receive the bolt, which has been referred to. The 60 upper horizontal part of the leg C² is expanded transversely, as at e, and is constructed with an elongated opening or slot, e'. (See Figs. 65 7, 7.) The vertical part of this leg C² has formed upon it an ear, d.

70 I am aware that Patent No. 146,224 shows a disk-gang connected at both ends by hangers to a supplemental frame, which, in turn, is connected to the transverse bar of the main frame by a vertical pivot, forked at its lower 75 end to receive the supplemental frame and rotating in the same frame.

75 I am also aware that Patent No. 259,919 shows a hanger forked at its lower end, with a disk-gang pivoted therein so as to vibrate 80 in vertical planes relative to the hanger, the hanger being pivoted to the main frame by an arm, so that the hanger swings bodily in an arc of a circle about said pivot whenever the disk-gang swings or vibrates in a horizontal 85 plane.

85 I do not in this case claim either of the above-mentioned patented constructions, but believe I am the first to employ the combination, with the tongue and cross-bar of a 90 main frame, of non-rotating pendent hangers forked at their lower ends and slotted at their upper ends, bolts passing through the slots 95 and into the cross-bar, disk-gangs mounted

loosely in the forked ends of the non rotating hangers, whereby said disk-gangs can vibrate in both horizontal and vertical planes without any corresponding movement of the hangers, 5 and whereby, also, the disk-gangs and their non-rotating hangers can be adjusted toward and from each other on a line at substantially a right angle to the line of draft.

10 D D are rods or links firmly bolted to the tongue at their forward ends and formed at their rear ends into hooks or eyes d' d', which engage with the ears d d, and thus serve to support the transverse bar B against twisting strain in substantially the same manner as 15 is customary in many machines of this general character.

E E' designate, respectively, the upper and lower portions of a boxing which is constructed with a central recessed or hollow enlargement 20 or rib, E².

e e are perforated lugs cast upon both the upper and lower halves of this boxing for the reception of bol's, which secure the two parts firmly to each other. (See Figs. 4, 5, and 7.)

25 e' is a lug or stud projecting upwardly from the rib E² of the upper part of this boxing, and projects up into the slot c' of the hanger.

20 e² (see Figs. 3, 4, 5, 6, 8) are spurs or lugs projecting downwardly from the lowest part 30 of the rib E² of the lower part of the boxing, one of these lugs being placed upon either side of the bolt F, which is supported at its ends in the legs C² C³ of the hanger, the construction and relation of parts being such that 35 the boxing is supported loosely between these hanger-legs and the bolt F, as will be readily seen from an examination of the drawings. (See particularly Fig. 8, where the position of the bolt F between the lugs e² e² is indicated 40 by dotted lines.) The lug e' is, by preference, made hollow to serve also as an oil-cup, there being a small hole or duct extending from the bottom of the oil-cup through the upper member of the boxing. (See Fig. 6.)

45 G is a thimble, consisting, essentially, of a tube having flanges at its ends, with a ring or hoop, g, made, preferably, of wrought-iron, and shrunk onto the flange, or malleable iron driven tightly on. Each hoop is by preference a little wider than the flange on which it is mounted, and projects inwardly so as to overlap the adjacent end of the boxing, which is round in cross-section, and fits closely within the hoop in such manner as to assist materially in preventing dirt from entering between the sleeve and the boxing, thereby reducing friction and preventing the cutting away of the wearing-surfaces of these parts.

50 H is a gang-axle.

60 I I are disks mounted upon the axle, and properly spaced by means of thimbles of any usual or approved construction, and in practice I propose to apply nuts or other clamping devices to the ends of the axles in such 65 manner as to firmly bind the disks, the thimbles, and the axles to each other, so that they shall all rotate together, and that the thimble

G shall rotate with the axle inside of the boxing E E'.

J J are draw-bars or links connected at 70 their forward ends to a lever, K, which is pivoted to the tongue, there being some locking devices used in combination with the lever and tongue, so that the lever may be set in any desired position. The rear end of each 75 of these draw-bars J is connected to one of the gangs of disks, preferably, by means of a boxing or strip which surrounds one of the thimbles, and has a perforated ear to receive a corresponding hook or eye of the draw-bar; 80 but as any of the convenient or approved form of lever or devices for connecting the rear ends of these draw-bars with the gangs may be used, it is not necessary to describe them in detail. Lever and draw-bars J J are employed 85 for moving the gangs into different positions or at different angles relative to the line of draft, and from an examination of the drawings it will readily be seen in Figs. 4, 5, 6, 7 that the boxing E E' can vibrate in a horizontal plane by reason of its being loosely mounted between the forked legs of the hanger, it being, of course, understood that when the harrow is in operation the weight of the rear 90 end of the frame and of the driver is supported upon the upper surface of the rib E², which 95 engages with the lower surface of the slotted portion c of the hanger, the space between the lugs e² and the bolt F permitting the desired vibration of the gangs into a horizontal plane 100 without undue cramping of parts. It will also be seen by examining the drawings that the disk-gangs can vibrate in vertical planes by reason of the same looseness of parts, when such vibration is desirable, in order that the 105 gangs may conform to any irregularity in the surface of the ground over which they are drawn.

In Figs. 3, 4, and 6 I have shown the boxing E E' as resting upon the bolt F and out of 110 contact with the forwardly-projecting horizontal part of the hanger-leg C². This I did in order to show (particularly in Figs. 3 and 4) the lug e'; but it will, of course, be understood that when the machine is in operation the 115 relative position of these parts is reversed—that is to say, that the upper part of the boxing is in contact with the under surface of the horizontal part of the bracket-leg C² and out of contact with the bolt F, except that the vertical vibrations of the gangs might sometimes 120 produce a contact between the bolt F and the adjacent part of the boxing.

By reason of the rods D D having hooks at 125 their rear end which take into the ears d d, the hangers and gangs can be adjusted horizontally upon the cross-bar B without cramping or straining any of the parts whenever such adjustment is desirable in order to increase or diminish the distance between the 130 inner disks of the gangs.

What I claim is—

1. In a disk-harrow, the combination of a tongue, the transverse bar rigidly attached to

- the tongue, two disk-gangs and the bearings in which they rotate, non-rotating hangers, each slotted at its upper end and forked at its lower end, which is arranged between two adjacent 5 disks of a gang, the bolts F F in the lower ends of the forked hangers, and the bolts b b, passing through the slotted upper ends of the hangers, the shaft-bearing being mounted loosely in the lower ends of the forked hangers, 10 whereby the gangs are adapted to vibrate in both horizontal and vertical planes, and to be adjusted toward and from each other on a line at a right angle to the line of draft, substantially as set forth.
- 15 2. In a disk-harrow, the combination, with the tongue and the transverse bar, of the forked hangers, each open at its lower end, the bolts mounted in the lower ends of the forked hangers, the axles and the bearings provided 20 with the lugs arranged upon opposite sides of the bolt, and mounted loosely in the hangers, and adapted to engage with one leg of each

hanger when the harrow is drawn forward, substantially as set forth.

3. In a disk-harrow, the herein-described 25 forked hanger having the leg C², provided with the transversely-slotted part c, the bolt at the lower end of the fork, and the bearing loosely supported between the bolt and the fork of the hanger, and provided with a lug projecting 30 into the transverse slot, and with the lugs e² e², substantially as set forth.

4. In a disk-harrow, the herein-described forked hanger having the leg C², provided with the transversely-slotted part c, the bolt at the 35 lower end of the fork, and the bearing provided with the enlargement E², the lugs e² e², and the hollow lug e', arranged in the slot c', substantially as set forth.

In testimony whereof I affix my signature 40 in presence of two witnesses.
